UNITED STATES PATENT OFFICE.

ANDREW J. THALMAN AND ALBERT A. HART, OF RICHMOND, CALIFORNIA.

SWIVEL-HEAD HYDRANT.

1,120,861.

Specification of Letters Patent. Patented Dec. 15, 1914.

Application filed June 16, 1914. Serial No. 845,381.

To all whom it may concern:

Be it known that we, ANDREW J. THALMAN and ALBERT A. HART, citizens of the United States, residing at Richmond, in the county of Contra Costa and State of California, have invented new and useful Improvements in Swivel-Head Hydrants, of which the following is a specification.

This invention relates to hydrants. 10 It is an object of the present invention to provide a simple, practicable and inexpensively manufactured swivel head hydrant.

It is a particular object of the present invention to provide a swivel head hydrant with as few parts as is possible with practical construction, and to provide a nozzle or head member capable of being turned through a complete circle, and to provide a lever having the dual functions of an operating means and a locking means to hold the hydrant head in any desired position with relation to the stand-pipe.

The invention consists of the parts and 25 the construction and combination of parts as hereinafter more fully described and claimed, having reference to the accompanying drawings, in which—

Figure 1 is a side elevation of the hydrant. Fig. 2 is a central, vertical section through the hydrant in a plane at right angles to Fig. 1.

In the drawings, 2 represents a stand-pipe connectible to a suitable source of supply 35 and having secured at its upper end an annularly flanged member 3, the diametral face 4 of which is adapted to form a seat; and centrally within the seat member 3 there is formed or provided a stationary 40 bushing 5, internally threaded as at 6 and forming a nut. Mounted upon the hydrant seat 3 is a hydrant head 7, here shown as of spherical form, with a radial nozzle or discharge mouth 8 at one side, and having 45 a flange or bearing face 9 to fit and turn upon the surface 4 of the valve seat 3. Extending diametrically through the hydrant head 7 and projecting from the top thereof is a valve spindle 10 having intermediate 50 its ends a stop shoulder 11, and also a bearing shoulder 12, and against the latter there rests a disk plate 13 turnable on the stem, forming the closing member of the valve; and being prevented from longitudinal 55 movement upon the spindle 10 by a pin or other suitable stop 14. The lower end of

the valve stem 10 is threaded as at 15 to engage the complementary threads of the nut 5 which is mounted against rotation as to and upon the seat member 3. 60

The upper end of the valve stem 10 above the hydrant head 7 may be provided with a suitable hand-wheel or other device 16 whereby the stem may be revolved, and through its engagement with the stationary 65 nut 5 the stem 10 will rise or fall according to the direction of its turning movement, so that the disk plate 13 will be lifted from or moved toward the valve seat 4 to control the discharge therethrough. The shoulder 70 11 of the valve stem 10 limits the upward movement of the valve and stem to prevent the screw 15 from passing entirely out of the nut 5. For the purpose of annularly turning the hydrant head 7 as to the stand-pipe 2, the hydrant head 7 is provided with 75 diametrically opposite depending journal brackets 17 which overhang the circumference of the flange of the valve member 3; and pivoted upon the journal brackets 17 80 of the hydrant head is a yoked lever 18, the ends of the arms of which are preferably formed with eccentric hubs or cam surfaces 19, which when the lever 18 is swung downwardly act to bind upon the lower surface 85 of the flange of the valve seat member 3, and temporarily but securely lock the hydrant head 7 in an angular position upon the valve member 3.

In addition to the depending journal 90 brackets 17 which overhang the flange of the member 3 other depending lugs 20 are formed on the flange 9 so as to embrace the circumference of the flange of the member 3, and thus prevent eccentric movement of 95 the hydrant head 7 as to the seat member 3.

The operation of the hydrant is as follows: With the several parts assembled as shown the operator may turn the hydrant head 7 so that the nozzle 8 thereof will 100 stand at the desired angle as to the stand-pipe 2 by grasping the operating lever 18 and tilting it about its pivot on the brackets 17, so as to disengage the locking surfaces 19 from the flange of the part 3. After having turned the hydrant head 7 by swinging it in a horizontal plane through means of the lever 18, the hydrant head may then be locked firmly in position by the downward movement of the lever 18 which will then 105 press the eccentric or cam surfaces 19 into contact with the contiguous flange of the

member 3 after which the hydrant head will remain in the desired angular position. The discharge of liquid or fluid through the valve is controlled by turning the hand-wheel 16 which turns the valve stem 10, this being given a longitudinal outward movement by the co-action of the threads 15 with the nut 5, and with the upward movement of the valve stem 10 the valve plate 13 10 is lifted from its seat 4 of the member 3, and thus allows the flow of liquid or fluid from the hydrant.

Having thus described our invention, what we claim and desire to secure by Letters Patent is:

1. In combination with a stand pipe, a member secured to the upper end of said pipe and having an outwardly extending peripheral flange, a nut connected to said member and arranged on the interior of the pipe, a head having a horizontal flange which turnably seats on the first named flange, a valve stem threadedly engaged with the nut and having a valve thereon which seats on the first named flange, depending guide elements connected to the flange of the head and extending over the periphery of the first named flange, and a pair of levers pivoted to two of said elements and having cams which bear against the under face of the first named flange.

2. In combination with a stand pipe, a member secured to the upper end of said pipe and having an outwardly extending peripheral flange, a nut connected to said member and arranged on the interior of the pipe, a head turnably seated on said flange, guide elements depending from the head and engaged over the periphery of said flange, a valve seating on the flange of said member and having a stem engaged with said head and threadedly engaged with said nut, means connected to said elements to enable rotation of the head, and means borne by said first named means for engagement with the under face of said flange to lock the head to the flange.

3. In combination with a stand-pipe and a horizontal flange connected thereto and extending outwardly therefrom, a valve engageable with the flange, a head to which the valve is connected turnably seated on said flange, and swingable means borne by the head and engageable with the under face of

the flange to enable the head to be locked to the flange and also turned on the flange.

4. In combination with a stand-pipe and a member connected thereto and extending outwardly therefrom, said member being formed to have a valve seat on one side face thereof, a head turnably seated on the member, a valve connected to the head and engageable with said valve seat, and swingable means borne by the head and engaged with said member to lock the head against turning movement and to also enable turning of the head.

5. In combination with a stand-pipe and a member connected thereto and extending outwardly therefrom, said member being formed to have a valve seat on one side face thereof, a valve engageable with said valve seat, a head connected to said valve and seated on said side face of the member in surrounding relation to said valve, and means connected to said head and engageable with the opposite side face of the member to lock the head against turning movement on said member.

6. In combination with a stand-pipe and a member connected thereto and extending outwardly therefrom, a valve and a turnable head connected to the valve which valve and head engage one side face of said member, and means connected to the head and engaged with the opposite side face of said member to lock the head against turning on said member.

7. In combination with a stand-pipe and a member connected thereto and extending outwardly therefrom, a valve and a turnable head connected to the valve which valve and head engage one side face of said member, a stem on the valve, means borne by said member and arranged on the interior of the pipe to engage the valve stem whereby upon turning of the latter the valve will be raised or lowered, and means connected to the head and engaged with said member to lock the head against turning.

In testimony whereof we have hereunto set our hands in the presence of two subscribing witnesses.

ANDREW J. THALMAN.
ALBERT A. HART.
